UNITED STATES PATENT OFFICE

HENRY L. WEBSTER, OF CHICAGO, ILLINOIS, ASSIGNOR TO WM. WRIGLEY JR. COMPANY,
OF CHICAGO, ILLINOIS, A CORPORATION OF DELAWARE

PACKAGE MAILING CARD

Application filed May 27, 1931. Serial No. 540,232.

This invention relates to improvements in package mailing cards, and more particularly to devices for transporting small packages and articles through the mail and 5 having the form of a combined container and address card.

The object of the invention is to provide a simple and convenient medium for the distribution of samples by mail, being primarily 10 intended for advertising purposes but adapted also for the mailing of small articles such as can accompany an address card at the same postage rate.

The mailing card herein disclosed is one 15 intended for the distribution by mail of sample packages of chewing gum or like products, and a further object of the invention is the provision of a container which will resist attempts to remove the contents 20 without breaking open or mutilating the same to such an extent as to be readily detected.

A preferred embodiment of the invention is disclosed in the accompanying drawing in 25 which

Figure 1 is a perspective view of the card filled and sealed for mailing, and

Figure 2 is a perspective view of the 30 several parts including the package separated to show the manner in which they are assembled.

The mailing card is preferably arranged to carry the accompanying contents at one end and on one side of the body of the card, 35 leaving the front or reverse side free for the address and postage. In this case, the length of the package is the same as the width of the card, so that with its enclosing container it forms a rectangular enlargement across 40 one end.

The body 1 of the card is of any suitable grade of heavy paper or cardboard, having one end portion folded to provide the outer enclosure 2 for three sides of the contents, 45 consisting of three connected wall sections,

namely, an outer end wall 3, a top or intermediate wall 4, and an inner end wall 5, the remaining wall of the enclosure opposite the top wall 4 being a portion of the card body adjacent the package carrying end thereof. 50 Beyond the inner end wall 5 is a wide flap 6 slightly wider than the package container, this flap being adapted to lie flatwise against the body of the card after the package has been inserted and fastened down by staples, 55 adhesive or other fastening members.

At the center of the free edge of the flap 6 is a tab 7 for convenience in tearing the flap 6 from its fastening to the body of the card. So much of the mailing card is made from a 60 blank which prior to folding is approximately one-half again as long as the folded card, the blank being scored along parallel lines to form the fold lines separating the several walls and the single flap 6, there being no score line between the tab 7 and the flap 6.

To complete the container, an inner band 8 of cardboard is provided which passes the long way around the package P and transversely to the outer enclosure which does not cover the ends of the packages. This inner band 8 preferably consists of a strip of cardboard of the width of the package and of a length to encircle the package, with its end 70 portions overlapping and provided with interlocking notches 8^a to join the ends together. The band is scored crosswise to form the fold lines at the end edges of the package so that when the band is folded into rectangular form and the ends joined, a rectangular enclosure is formed into which a passage may be inserted edgewise. Along one edge of the larger section of the band is a flap 9 projecting outwardly in the plane 75 thereof, said flap being adapted to lie between the body of the card and the outer flap 6. 80

Thus to enclose a package in the mailing card, the package P is first inserted into the band, which is either folded preparatory to 90

receiving the package, or the flat strip is folded around the package and the end joined as shown in Figure 2. The partially enclosed package is then centered transversely of the card, so that when the several outer wall sections are brought around the package, the end flap 6 bears flatwise against the body of the card, with the flap 9 of the inner band 8 therebetween. And finally to complete the enclosure of the package, staples 10 are driven through the two flaps and the body of the card near the opposite edges thereof.

When the mailing card and contents reach the addressee, an upward pull on the tab 7 releases the outer flap from the staples, permitting access to the package.

To increase the effectiveness of this mailing card and add to its advertising value, the exposed sides or panels of the package enclosure may be printed so as to simulate the color and dress of the package within. So too the card may bear other advertising matter on the body thereof, with the customary space for address and postage in conformity with the postal regulations.

By the use of such a container formed integral with a mailing card, the contents are completely enclosed so that they cannot be tampered with or removed without breaking the seal, or tearing away the ends of the band, since the package cannot be reached by sliding it bodily endwise from the outer enclosing walls so long as the parts are held in place by the staples.

Having set forth a preferred embodiment of my invention, I claim:

1. A mailing card for the purpose described, comprising a card having a portion along one edge folded inwardly and over upon the body of the card to form therewith an integral container consisting of connected walls adapted to surround three sides of the contents and a flap adapted to bear flatwise against the body of the card, a band adapted to extend around the contents at right angles to said walls, and means for fastening said band and flap to the body of the card.

2. A mailing card for the purpose described, comprising a card having a marginal portion folded transversely over upon one face thereof to form therewith a plurality of connected sections adapted to surround the contents in one direction, and a flap adapted to lie flatwise against the body of the card, a separate band adapted to surround the contents in the opposite direction, and having a portion extending from one edge thereof, said contents in their surrounded band being adapted to be enclosed within said walls with the extended flap portion of said band beneath said flap, and a fastening member inserted through said flap, the extended edge portion and the body of the card.

3. A mailing card for the purpose de-

scribed, comprising a card having a portion along one edge folded inwardly and over upon the body of the card to form with the adjacent portion of the said body an open-ended enclosure and a flap adapted to be secured flatwise against the card after the contents have been inserted in the enclosure, and a separate closure member for the ends of said enclosure and having a portion extending beneath said flap.

Signed at Chicago, Ill., this 23d day of May, A. D. 1931.

HENRY L. WEBSTER.
